UNITED STATES PATENT OFFICE.

LAURENT RONDOLIN, OF BERMONDSEY, ENGLAND, ASSIGNOR TO PEEK FREAN & COMPANY LIMITED, OF LONDON, ENGLAND.

MACHINE FOR APPLYING CREAM AND LIKE MATERIALS TO BISCUITS AND THE LIKE.

Original application filed September 18, 1924, Serial No. 738,375. Divided and this application filed May 9, 1925. Serial No. 29,179.

To all whom it may concern:

Be it known that I, LAURENT RONDOLIN, a subject of the King of Great Britain and Ireland, residing at Bermondsey, in the county of London, England, have invented Improvements in or Relating to Machines for Applying Cream and like Materials to Biscuits and the like, of which the following is a specification (division of No. 738,375, filed September 18th, 1924).

This invention relates to machines of the kind in which material such as cream and the like is applied to biscuits and the like, automatically from a hopper with the aid of two endless travelling webs one whereof serves to support the biscuits or other articles whilst the other which surmounts the same serves as a shape and thickness determining controller for the coating to be applied.

The object of the present invention is to provide an improved construction of travelling web for supporting the biscuits.

In the accompanying drawings, Fig. 1 is a semi-diagrammatic elevation of both belts of a machine such as referred to. Fig. 2 is a plan to a larger scale of a portion of the lower belt of Fig. 1. Figs. 3, 4 and 5 are sections corresponding to the lines 3—3, 4—4 and 5—5 of Fig. 2.

In Fig. 1, 1 is the endless carrier belt upon which the biscuit blanks are received and 2 is the stencil belt associated therewith. The two belts are caused to travel in synchronism, the biscuit blanks that are to be coated being abstracted from a pile seriatim by positioning devices upon the belt 1 so that they ultimately register with the openings in the stencil belt 2. The stencil belt is associated with the outlet of the hopper that contains the coating material and the coating takes place when an individual blank with its registered stencil opening are themselves both in register with the outlet aforesaid. As the two belts with the blank therebetween leave the outlet of the hopper, the stencil belt sweeps past the latter and so wipes off excess coating material, from which it will be understood that the thickness of the coating is determined by the thickness of the stencil belt. The carrier belt 1 as shown in Figs. 2 to 5 consist of two relatively thick but narrow lengths or runs 3 of leather or the like spaced apart and held

at the proper distance one from the other by transverse metal ties 4 adapted to support a thinner mid-run 5 of suitable material such as a silk belt which serves to directly receive the biscuit blanks and is interrupted at intervals by pins 6 adapted to dislodge blanks from a guide container such as is described in the specification of my application, Ser. No. 738,375, filed September 18th 1924, said pins 6 which constitute the blank abstracting devices referred to being riveted to the ties 4. If desired, canvas and like pads 8 may be sewn to the underside of the silk belt 5 substantially equal in thickness to the ties 4. The spaced runs 3 may be secured to driving chains 9 by pins 10 that project laterally from certain of the chain links. Certain links are shown as having studs 11 adapted to cooperate with holes in the stencil belt 2 which is thus driven, such an arrangement ensuring register between the biscuit blanks and stencil perforations in the belt 2, through which the cream or the like passes, that is not attainable or easily attainable by independent positive driving of the belts.

What I claim is:

1. In a machine of the kind herein referred to, a carrier belt comprising two relatively thick but narrow endless runs, transverse metal ties holding the said runs in spaced relationship and a thinner mid-run supported between the spaced runs aforesaid by the metal ties, substantially as described.

2. In a machine of the kind herein referred to, a carrier belt comprising two narrow endless runs, a thinner endless run perforated at intervals in its length and metal ties connecting the narrow endless runs at a distance apart such as to accommodate the thinner endless run therebetween, said ties having pins which extend through the perforations in the said thinner run, substantially as described.

3. In a machine of the kind herein referred to, a carrier belt comprising two narrow endless runs, a pair of endless chains, and pins projecting laterally from such chains into the endless runs, substantially as described.

Signed at London England this 22 day of April 1925.

LAURENT RONDOLIN.
